(57) The ornamental design for a base handbag for use with an interchangeable cover, as shown and described.

DESCRIPTION

FIG. 1 is an exploded top, left perspective view of an interchangeable cover for use with a base handbag when the base handbag is withdrawn from the handbag cover, with the interchangeable cover shown with attachment flaps in an open position;

FIG. 2 is a front elevational view thereof, with the rear elevational view being a mirror image thereof;

FIG. 3 is a left side elevational view thereof, with the right side elevational view being a mirror image thereof;

FIG. 4 is a bottom plan view thereof; and,

FIG. 5 is a top plan view thereof.

The broken, alternating long and short lines are for the purposes of illustrating environment, or hidden elements, and form no part of the claimed design. The evenly spaced broken lines represent stitching and are part of the claimed design.
